UNITED STATES PATENT OFFICE.

LEON MANN, OF MOUNT VERNON, AND MORRIS KOPPELMAN, OF BROOKLYN,
NEW YORK.

PACKING FOR EGGS AND OTHER FRAGILE ARTICLES.

Application filed January 11, 1924. Serial No. 685,502.

To all whom it may concern:

Be it known that we, LEON MANN, of the city of Mount Vernon, in the county of Westchester and State of New York, and MORRIS KOPPELMAN, of the borough of Brooklyn, in the county of Kings, city and State of New York, citizens of the United States, have invented certain new and useful Improvements in Packings for Eggs and Other Fragile Articles, of which the following is a specification.

The improvements relate to packing for fragile articles such as eggs, electric light bulbs, bottles and other articles which are usually of a more or less globular form, made of brittle material such as glass and china, and more particularly to packing of this character which is adapted to space and hold such articles and protect them against breaking shocks and strains in storage, shipment and handling.

In the application of the improvements illustrated in the drawings the packing is used for the purpose of holding and protecting eggs in a carton adapted to be used for packing, shipment and storage, but it will be understood that there are other uses to which they may be put, either with or without modification.

In the said drawings Fig. 1 is a side view of a box or carton with packing devices therein embodying the improvements, one end of the box being broken away to disclose the interior; Fig. 2 is a longitudinal vertical section of one end of the box shown in Fig. 2 with the packing and articles packed therein; Fig. 3 is a detail view of one of the article holding cups or receptacles of the packing; Fig. 4 is a plan of two of the said receptacles and adjacent portions of the sheet on which they are mounted.

The box A may be of any suitable form. As shown it consists of ordinary paper board folded into a rectangular enclosure and having an openable lid or cover A¹ with a flap A² adapted to be passed down inside the box and between one of its walls and the edges of the packing members to close the box.

The sheets B are preferably formed of paper pulp and have integral therewith the

recesses or cups C, the sheet and recesses being best formed by a felting process, so that the material will be of substantially uniform strength and thickness, and will not have weak spots or breaks in it, as would occur if it were attempted to form the packing from flat sheets of material.

In the present instance the cups or recesses are of a size and shape adapted for the packing of eggs, electric light bulbs and bottles of certain forms, and have a zone of depression C¹ extending from the sheet B on curved converging lines and a depression C² at the bottom thereof curved on a smaller radius and extending from the bottom of the depression C¹ to proximity to the box or casing. The depression C¹ is adapted to receive and conform approximately to the exterior of the article to be held, the lines of junction of the same with the sheet B and the depression C² forming friction or gripping points, and holding the article against lateral movement with or without assistance of the portions between these lines, and the depression C² forming a buffer or cushion to protect the article against shocks from the outside and also causing, when pressure is exerted thereon a certain flexing action of the walls of the portion C¹ so that it will maintain a slightly resilient grip on the article. The packing however should be formed of relatively heavy and rigid material, so that it will not give way or be deformed by the ordinary stresses of use but will return at once to normal shape after being flexed by any strain.

In use the lower packing member is first placed in the bottom of the box or carton with the cup-form recesses downward, and the articles to be packed placed individually therein, another member is then placed on the top of the articles inverted so that its recesses will receive the upper portions of the articles and be aligned with those of the lower member. The box may then be closed. It will be observed that sheets B fill the box laterally from side to side and from end to end and the cups, with articles therein fill it from side to side. The height of the box will of course depend upon the length of the article held between the packing members, and should be such that the domes C² are in

contact with its top and bottom. If desired however the upper or lower packing member may be omitted, and a sheet of corrugated paper or a pad inserted in its place, 5 if necessary. It will be found that the cups will hold the articles effectively against lateral movement though only one set is used.

If the articles are of the same diameter as the combined depth of the cups the sheets 10 B will be brought together so as to completely enclose the article, and in the packing of eggs or any other article cups of sufficient depth to bring about this result may be used. In the illustrative embodiment of the improvements shown in the 15 drawings the cups are formed primarily for use in the packing of one layer or tier, as in the ordinary parcels post or retail store package. It is obvious that where the eggs 20 or other articles are packed in crates or other receptacles, tier on tier, it will be advantageous to have the cups of sufficient depth to permit the sheets B to be in contact, so that the weight of a tier is supported 25 by the packing of the tier below and not imposed on the eggs themselves. It is further obvious that where superposed tiers are used, the packing sheets with their cups may be cut or formed so that the articles and 30 their cup holders will be in staggered relation with the domes C² of one layer located in the depressions between the cups, and forming shock absorbing supports.

By means of this packing a standard 35 crate of eggs may be filled, without the use of fillers or any other packing member than the ones herein described, and the eggs removed a dozen—or more or less—at a time in a box or carton which may be taken away. 40 by the retail customer. The boxes or cartons shown may be dispensed with when the eggs or other articles are packed in crates, as the sheets B with their recesses and sub-recesses will afford sufficient spacing and protection 45 when the said articles are packed in superposed layers or tiers, with or without fillers. A similar practice may be followed in the packing, shipment and sale of other articles. It will also be apparent that the boxes may 50 be opened and the articles removed therefrom in the lower packing member and placed upon a counter or other support for examination, and returned to the box, without handling.

55 The size and proportions of the parts of the packing members may be varied, and other changes made in details without departing from the scope of the invention.

What we claim is:

60 1. A packing for fragile articles adapted to be placed in a suitable box or other enclosure comprising a sheet of material having a series of cup-like depressed portions formed therein and adapted to receive articles to be packed and hold them in spaced

relation, the said depressed portions having substantially conical bottom portions of relatively small diameter forming extensions of the main cup-like depression, and adapted to extend beyond the article therein. 70

2. In the packing specified in claim 1, the said sheets, depressions and extensions thereof being formed of a continuous piece of fibrous sheet material.

3. In the packing specified in claim 1, 75 the depressions being separated and spaced from one another by portions of the sheet of material, and the said sheet of material extending laterally beyond the outermost of said depressed portions.

4. The combination with a box or like enclosure of a sheet of packing material adapted to be placed in said box and to receive articles to be packed therein and hold them in spaced relation, said sheet of packing material having article receiving depressions therein and bottom sub-depressions of relatively small diameter and extending over a relatively small portion of the main depression. 80

5. In the combination specified in claim 4 the said sheet extending laterally from side to side and from end to end of the enclosure and the said bottom sub depressions extending to proximity to another side of said enclosure. 85

6. In the combination specified in claim 4 the said sheet of packing material being constructed and arranged to be placed either in the top or the bottom of the receptacle. 90

7. In combination with the devices specified in claim 4, a second similar sheet of packing material adapted to be placed on the opposite side of the enclosure from the first, both sheets being less than half the 100 diameter of said enclosure, the said sheets when so disposed having the depressed portions opposite one another with their mouths opposed, and adapted to receive an article between them and hold against vertical as well as lateral movement.

8. A packing for fragile articles comprising a sheet of relatively rigid fibrous material having a series of spaced depressed portions and lateral portions connecting and spacing the same and extending beyond the outermost depressed portions, the said depressed portions having extensions of relatively small diameter at the bottom only, and said sheet adapted to receive one end portion of the article to be packed, the construction and arrangement being such that another similar sheet may be placed so as to receive the opposite end portions of articles in the depressions of the first sheet 115 so that the said articles are held therebetween and out of contact on all sides with one another and with objects such as the walls of a box or other enclosure. 120

9. A packing for fragile articles adapted 125

to be placed in a suitable box or other enclosure, comprising a piece of sheet material having a series of cup-like recesses formed therein and adapted to receive articles to be packed and hold them in spaced relation, said recesses having sub-recesses at the bottom only and of relatively small diameter forming extensions of the main re-

cesses, and adapted to extend beyond the article placed therein. 10
Witness our hands this 9th day of January, 1924, at the borough of Manhattan in the city, county and State of New York.

LEON MANN.
MORRIS KOPPELMAN.
